UNITED STATES PATENT OFFICE.

GEORGE BINET DOREY, OF MONTREAL, QUEBEC, CANADA, ASSIGNOR TO WILLIAM H. MINER, OF CHAZY, NEW YORK.

FRICITION DRAFT RIGGING.

Application filed March 13, 1922. Serial No. 543,430.

To all whom it may concern:

Be it known that I, GEORGE BINET DOREY, a subject of the King of Great Britain, and residing in the city of Montreal, Province of Quebec, Dominion of Canada, have invented certain new and useful Improvements in Friction Draft Rigging, and do hereby declare the following to be a full, clear, and exact description of the same.

10 My invention relates to improvements in friction draft riggings as used in railway cars and the like and is especially related to that class wherein wedges are used in connection with friction elements and springs 15 for the purpose of generating friction.

An object of the invention is to provide a central frictional member within a casing and to cause friction shoes to engage the said frictional member and move relatively thereto and to provide suitable wedging means to ensure frictional contact.

20 It is also an object of the invention to provide pressure transmitting members having a short travel and adapt the same to displace 25 other friction elements a correspondingly greater distance and at a relatively greater speed.

30 A further object of my invention is to produce a friction draft rigging which will give a variable resistance, providing for a light resistance at the commencement of the compression movement and a differentially increasing capacity as the range of movement increases.

35 A further object of the invention is to provide a structure wherein the central frictional element will be relatively stationary to the casing and not subjected to transverse displacement or bending stresses.

40 Further my invention consists in certain other features of novelty such as will be more particularly pointed out in this specification and claims.

45 For a fuller comprehension of my invention reference must be had to the accompanying drawings wherein like references indicate like parts and wherein:

50 Figure 1 is a horizontal sectional view through the complete rigging as assembled and applied between the sills of a railway car, the parts being in the normal or extended position.

55 Figure 2 is a sectional view taken on line 2-2 of Fig. 1.

Figure 3 is a horizontal sectional view 65 as shown in Fig. 1, showing the rigging under full compression.

Figure 4 is a longitudinal side view of the rigging taken on line 4-4 of Fig. 1, showing the rigging bolted together as a self-contained unit.

Figure 5 is a perspective view of the casing showing a portion thereof in section.

Figure 6 is a perspective view of the central friction member.

Figure 7 is a perspective view of one of the friction shoes.

Figure 8 is a perspective view of one of the wedge block pressure transmitting members.

Figure 9 is a perspective view of the wedge retaining member.

In the drawings 2 represents the drawbar of the coupler connected by means of key 3 to the yoke 4 in the usual manner, the yoke 75 embracing the casing 5 and the whole being located between the center sills 6-6. The rear of the casing 5 is formed to abut against rear stops 7-7 which are secured to the center sills by means of rivets 8, front stops 9-9 also secured to the center sills in like manner constitute draft gear abutments under pulling strains.

The draft rigging as illustrated in the drawings consists of the casing 5, central 85 friction member 10, friction shoes 11, wedge retaining member 12, wedge block pressure transmitting members 13, follower 14, outer spring 15 and inner spring 16. The central friction member is secured against outward 90 movement by means of bolt 17 and nut 18, the central friction member being recessed at 10^a to accommodate the nut.

The casing 5 is preferably formed of rectangular section with one end closed and the other end open and formed at each side near the open end with two sets of co-extending friction surfaces as shown at 5^a and 5^b. Surfaces 5^a being parallel to the longitudinal line of draft and surfaces 5^b being inclined thereto. Abutments 5^c are disposed in each corner of the casing and constitute bearings for the ends of the beams 10^b of the central friction member 10. These beams extend from one side of the casing to the other and are substantially parallel with the lateral walls of the casing and act as supports for the crossbeam 10^c which divides the casing.

The crossbeam 10^c is provided with a depending portion extending inwardly into the casing which is formed on either side thereof with bearing surfaces 10^a preferably made 5 flat and adapted to co-act with the interior surfaces 11^a of the friction shoes 11. The friction shoes 11 are adapted to have reciprocatory motion on the friction member 10 and in order to insure frictional engagement 10 between these members the former are formed with wedge shaped surfaces as at 11^b adapted to co-act with similarly inclined surfaces 12^a of the wedge retaining member 12.

15 The wedge retaining member is forced tightly over the inclined portion of the shoes by the tension in the outer spring 15 which abutting on surface 12^b thereby resists inward movement of the shoes. The 20 exterior of the shoes at the inner end as at 11^c are preferably curved and project beyond the surface 12^b of the wedge retaining member thereby forming a medium for centering the outer spring and securing the 25 same against lateral displacement. The end of the shoes as at 11^d are preferably made flat and form a bearing for inner spring 16 which directly opposes inward movement of the shoes and also operates to break the engagement 30 between the wedge retaining member and the shoes thereby facilitating the releasing of the rigging.

The outer ends of the shoes are also 35 formed with exterior wedge shaped surfaces as at 11^e and these surfaces are adapted to register with similarly formed surfaces 13^a of the wedge pressure transmitting members 13. Pressure applied on the wedge blocks in a longitudinal direction is 40 resolved in part into a transversely acting force against the casing walls due to the inclination of the walls 11^e of the shoes. During the early stages of the compressive action 45 of the rigging, walls 13^b of the wedge blocks co-act with walls 5^a of the casing but at a later stage in the gear's compression movement inclined walls 13^e move into engagement with walls 5^b of the casing thereby 50 communicating to the wedge block pressure transmitting members a transverse as well as a longitudinal motion. This transverse motion results in frictional action between faces 13^d of the wedge blocks and inner surface 14^a of the follower 14 inasmuch 55 as these surfaces are preferably at right angles to the line of draft.

When the gears are assembled both the inner and outer springs are placed under 60 initial compression, the friction member 10 having a hole 10^e extending throughout its length for the reception of bolt 17 and by means of which the friction member is secured to the rear of the casing. The abutting faces 10^f of the laterally extending beams 10^b are adapted to engage the lugs

13^e which are formed on the wedge block pressure transmitting members thereby causing these members to become a portion of the self contained gear as shown in Fig. 4.

The operation of the draft rigging takes place as follows:—In draft or buffing the draft rigging is compressed by the approach of follower to casing, the rear of the casing abutting against rear stops. This movement causes wedge block pressure transmitting members 13 to be moved longitudinally into the casing 5. During such movement the walls 13^b of members 13 co-act with parallel walls 5^a of the casing forcing the former outwardly against the casing wall by reason of the inclined exterior walls 11^e of the shoes co-acting with interior wedge shaped surfaces 13^a of members 13, and consequently the pressure transmitting portion of the rigging as composed of the follower and wedge block pressure transmitting members move longitudinally into the casing in unison with the load resisting portion of the rigging as composed of the shoes and wedge retaining member. The transverse reaction of the members 13 against the casing walls results in the shoes being forced against the central friction member 10 and this transverse force is further augmented by the pressure of the outer spring acting on the wedge retaining member in the manner already explained.

Continued inward movement of members 13 results in wedge surfaces 13^e which extend longitudinally of the gear and are disposed side by side for a portion of their length with surface 13^b but inclined thereto making contact with inclined walls 5^b of the casing thereby causing the members 13 to move transversely towards each other as well as in a longitudinal direction. As these members move transversely towards each other it will be seen that the interior wedge faces 13^a will be brought closer to each other thereby creating a squeezing effect on faces 11^e of the friction shoes causing these members together with the wedge retaining member to move a greater distance than the wedge block pressure transmitting members and therefore at a greater speed. Inasmuch as the wedge block pressure transmitting members move longitudinally into the casing at drawbar speed it follows that the load resisting members will move a greater distance and therefore at a greater speed than the drawbar. The transition from low to high resistance is thus accomplished without altering the angle between the bearing faces of the shoes and pressure transmitting members, these surfaces each composed of a single face remaining in contact and parallel to each other irrespective of any variation in the speed of the load resisting members.

Upon the maximum compression of the gear being attained the surface 14^a of the follower 14 is adapted to abut on the casing edge at 5, this latter member taking the 5 solid blow and thereby relieving the friction mechanism of undue strain.

Both the inner and outer springs being compressed and the gear solid, release takes place as follows:—

- 10 The springs reassert themselves returning the friction shoes with the wedge retaining member in a forward direction forcing the wedge block pressure transmitting members in an outward and forward direction and re-
15 turning therewith the follower and drawbar to the normal release position.

Any tendency of the shoes binding on the central friction member is prevented by the inner spring which bearing directly on the 20 ends of these members forces them slightly out of engagement with the wedge retaining member thereby loosening the frictional adherence between the parts.

From the preceding description it will be 25 noted that the central friction element being supported near the open end of the casing is free from bending strains and is subjected only to shearing and tensional strains during the compressive action of the 30 rigging. The use of a friction member mounted in the casing in the manner described permits the production of an unusually compact rigging and one wherein all the parts are secured against displacement. 35 The lateral beams extending from side to side of the casing centralize the friction member and the depending portion of the same extending inwardly serves to centralize the inner spring within which it is 40 extended.

While I have shown and described one particular embodiment of my invention it is evident that certain changes and modifications may be made without departing from 45 the spirit and scope of the claims.

What I claim is:

1. In a friction draft rigging a wedging element having a plurality of surfaces disposed at varying angles and adapted to come 50 into action successively, the said surfaces extending side by side longitudinally of the gear for a portion of their length.

2. In a friction draft rigging the combination of movable elements and relatively sta- 55 tionary elements each having a plurality of friction faces, the said faces being disposed at different angles with the line of draft and extending side by side longitudinally of the gear for a portion of their length.

3. A friction draft rigging comprising a 60 relatively stationary member, a drawbar movable relatively thereto, pressure transmitting members in sliding engagement with the stationary member and movable in uni- 65 son with the drawbar, resistance members in

engagement with the said pressure transmitting members and adapted to be displaced thereby a greater distance than the drawbar moves and means whereby the speed of the resistance members is increased during such 70 movement at a predetermined point.

4. A friction draft rigging comprising a casing, pressure transmitting members, one side of each member being formed with a single face and an adjacent side being 75 formed of a plurality of faces disposed at varying angles and adapted to engage the casing successively.

5. A friction draft rigging comprising a casing, a beam dividing the same and friction shoes engaging the said beam, transversely and longitudinally movable pressure transmitting members acting on the shoes to displace the same. 80

6. A friction draft rigging comprising a 85 casing having beveled walls, wedge pressure transmitting members in engagement therewith, a beam extending across the casing and having a depending portion extending inwardly therein, friction shoes having interior faces in engagement with the said beam, the shoes having their ends formed with oppositely disposed wedge shaped outer faces; one end of each shoe having engagement with the wedge pressure transmitting members and the other end being engaged by a wedge retaining member and springs opposing inward movement of the 90 parts. 95

7. A friction draft rigging comprising a 100 casing having beveled walls, wedge pressure transmitting members having adjacent inclined surfaces, one of such surfaces engaging the beveled walls of the casing and the other of such surfaces engaging movable 105 shoes, the said shoes being in sliding engagement with a central friction member extending from side to side of the casing and supported thereby.

8. In a friction draft rigging the combination with a movable drawbar of a casing provided with abutments and a beam supported thereon, friction shoes in engagement therewith and means in engagement with the casing for moving the shoes a 110 greater distance than the drawbar moves. 115

9. A friction draft rigging including a casing having one end open, side walls and an end wall, transversely and longitudinally movable pressure transmitting members having engagement with the side walls, a friction member carried by the side walls and spaced from the end wall, friction shoes engaging the said friction member and adapted to be moved by movement of the pressure 120 transmitting members. 125

10. A friction draft rigging including a casing having one end open, side walls and an end wall, the side walls being provided with beveled faces at the open end and 130

- wedge blocks sliding thereon, a friction member carried by the casing and spaced from the end wall, friction shoes engaging the said friction member and adapted to be 5 displaced by movement of the wedge blocks.
11. A friction draft rigging comprising a casing, abutments within the casing, a beam supported thereby, friction shoes in engagement with the said member, trans- 10 versely and longitudinally movable pressure transmitting members in engagement with the said casing and adapted to move the friction shoes and means for securing the said beam against outward movement.
12. A friction draft rigging having a casing presenting an end wall and having the opposite end thereto open, beveled walls at its open end, pressure transmitting members having sliding engagement on the said 15 beveled walls, friction shoes having their opposite ends formed wedge shaped, the said shoes having engagement with the pressure transmitting members at their outer ends and having engagement with a wedge 20 retaining member at their inner ends, the said shoes being adapted to have sliding engagement with a member supported by the casing walls, spring means interposed between the friction shoes and the end wall 25 and spring means interposed between the wedge retaining member and the end wall.

13. A friction draft rigging having a casing presenting substantially parallel side walls, pressure transmitting members having engagement with the said walls, a friction member disposed within the casing and friction shoes in sliding engagement therewith, the said shoes being each formed with inner and outer wedge shaped ends and an integral wedge retaining member adapted to 35 act upon the inner ends of the shoes to force the same into engagement with the friction member and the outer ends of the shoes being acted upon by the pressure transmitting members and springs for maintaining the 40 parts in operative relation.

14. In a friction draft rigging for railway cars, the combination of a stationary member and pressure transmitting members in 45 sliding engagement therewith and movable uniformly in a longitudinal direction, load resisting members adapted to be displaced by the pressure transmitting members variably in a longitudinal direction, such variation being effected by transverse movement 50 of the pressure transmitting members.

In witness whereof I hereunto affix my signature in the presence of two witnesses.

GEORGE BINET DOREY.
